 Joseph, Mich., a corporation of Michigan

Application January 4, 1946, Serial No. 639,015

6 Claims. (Cl. 254—2)

1

This invention relates to hydraulic jacks. The invention has been illustrated and described as most aptly applied to an hydraulic jack of the type known as "floor jacks," but the invention has other hydraulic jack adaptations.

Among the objects of the present invention is to provide an hydraulic jack wherein the pressure producing or pump mechanism comprises a relatively low pressure pump and a relatively higher pressure pump actuated from a common manually operated member, for creating a pressure in the ram cylinder, the arrangement being such as quickly to project the ram cylinder to a position such that the load lifting member is speedily brought to the work, at which time one of the pressure pump members, to-wit the low pressure pump member, cuts out, and thereafter the higher pressure pump member remains operative in the load lifting effort. The particular object of the invention is to provide a compact arrangement of relatively low and relatively high pressure pumps in combination with the ram cylinder and a common actuator for conjointly reciprocating the pumps, together with fluid pressure operated mechanism for cutting out one of the pumps and thereafter continuing the other one to raise the load.

Yet another object of the present invention resides in the provision of a floor jack embodying the foregoing constructions and characteristics and wherein the object of the invention is to provide mechanism for reciprocating two pumps from a single manual actuator, in a compactly arranged manner.

Yet another object of the invention resides in the arrangement of the relatively low and relatively higher pressure pumps disposed in parallel relation with respect to the longitudinal axis of the ram cylinder and at one end thereof, and in the intermediate disposition of the pressure relief valve for relieving the ram cylinder.

Other and further objects of the invention will be apparent from a perusal of the following specification, when taken in connection with the accompanying drawings, wherein:

Figure 1 is a perspective view showing the various parts of the floor jack in a central relation;

Figure 2 is a view showing certain of the parts removed from the chassis and showing the chassis itself;

Figure 3 is a top plan view, partly in section, of the chassis;

Figure 4 is a section taken on the line 4—4 of Figure 3;

2

Figure 5 is a section taken on line 5—5 of Figure 7;

Figure 6 is a perspective view of the oscillating sector for the pump mechanism;

Figure 7 is a sectional view taken on the line 7—7 of Figure 5;

Figure 8 is a section taken on the line 8—8 of Figure 5; and

Figure 9 is a section taken through the rear 10 end of the jack, and corresponding to Figure 4, and showing the work support in raised position.

Referring now to the drawings in detail, the jack comprises a chassis shown particularly in Figure 2, which includes an enlarged body section 15 formed of two vertically disposed side plates 2 and 4 which at the forward end are joined by a top plate 6 having a slight forward and downward inclination. This top plate 6 has two rearwardly extending ears 8 and 10 spaced apart 20 and provided with registering perforations 12 and 14 for the reception of a pivotal pin 16 hereinafter referred to. That section of the body portion to the rear of the top portion 6 is open at the top, as shown at 17. At this point the two side plates 2 and 4 are united by a rear transversely disposed wall 15 which in turn has a parallel extension in the form of vertical walls 16 and 18, and which are rigidly and integrally connected as at 20 by a top bridge portion for 25 rigidity. These vertical side walls 16 and 18 are interconnected as at 22 by a transverse integral web which has a depressed cup-like cross groove 24 formed at the top thereof. The rearmost portion 26 of the body portion 22 is provided with 30 registering openings for the reception of a stationary axle 30. A threaded pin 32 holds the axle 30 in position on the chassis 26. The opposite ends of the axle 30 carry stationary shields 36 and 38 which are pinned thereto as at 39 and 40, and casters or wheels 42 and 44 are 35 rotatably mounted on the opposite ends of the axle 30.

On the underside the body of the chassis is provided with two downwardly depending webs 46 and 48 for purposes of rigidity, and these webs are provided with registering apertures which extend parallel to and on the longitudinal axis of the chassis. One of these apertures such as 49 extends completely through the wall 48 while the aperture in the wall 46 is formed as a countersunk portion and is not formed completely through the wall. At the larger end of the chassis the underside thereof is provided with downwardly depending partitional walls or seats 50 and 52 which provide a mounting for a ram cyl-

inder, as shown in Figure 4. In other words, the underside of the chassis is substantially hollow except for certain of the rigidifying webs 46, 48, 50 and 52. The larger end of the chassis is provided with two integral outstanding shoulders 54 and 56, see Figure 3, each of which is provided with a vertical bore rotatably to receive each of which, as shown to the left in Figure 8, is a vertical bore rotatably to receive the turnable posts 58 and 60 of a caster wheel assembly comprising the ball bearing mounting 62 and the front shield 64 on which are mounted the axle 66 and rotatable caster 68. Means such as a pin 70 serves to hold the rotatable shank 58 of the casters in position on the shoulders 55 and 57, permitting them to rotate but preventing their withdrawal.

As shown in Figure 2, the larger end of the chassis body below the top 6 is formed as a vertical flat front plate 72 carrying the relatively large opening or bore 74 in line with the high pressure pump cylinder hereinafter referred to. In addition this plate 72 is provided with four spaced apart threaded bolt holes 76 which are adapted to receive the bolts 80 which bolt on that part of the body portion 82 in which the high pressure pump cylinder, the pressure relief valve, and the various ball controlled liquid passages are formed. As shown in Figure 2, this high pressure pump cylinder head carries affixed to it the ram cylinder 84 and its projecting ram 86. As shown in Figure 4, the ram cylinder snugly fits and lies within the webs 50 and 52. The body portion 82 includes the integral vertical plate member 75 from which the ram cylinder 84 projects. When the bolts 80 are tightened the vertical plate 75 of the body portion 82 is snugly tightened against the flat face 72 of the chassis, the ram cylinder 84 projecting into the opening 74 of this end of the chassis.

A load lifting carriage hereinafter described as mounted upon the pivotal pin 16, see Figure 9, passes through the perforated ears 8 and 10 of the chassis body 6 and also through a cross bore 96 of the downwardly extending section 98 of the load lifting member. This member has the two side flanges 100 and 102 which carry spaced apart bearing bores 104 and 106 adapted to receive a pin 108 which carries a roller 110. The elongated load lifting and lowering carriage 88 is shown in Figures 1, 2 and 9. It is provided with two vertical sides 90 and 92 and the transverse top 94. The forward end of this load carrying member 94, see Figure 2 is provided with two outstanding ears 112 and 114, which ears are perforated as at 116 and 118 to receive a pin 120, see Figure 1, which supports a load lifting head 122. This head has a centrally disposed annular flange 124 receivable in a snugly apertured bore 126, the apertures of which receive the flange 124 of the load lifter 122 whereby the load lifter 122 may rotate as desired. The flange 126 is provided with two spaced apart ears 128 and 130 which are supported by the cross pin 120. In addition the flange 126 carries two lateral toes 132 and 134 which receive a cross pin 136 connecting to links 138 and 139, the other ends of which are pivoted as at 140 to the side plates 2 and 4 of the chassis body. The purpose of these latter links is to maintain the rotatable work holder 122 in constantly horizontal position. When the load is in lowered position it will rest within the grooved cross slot 24 of the chassis, whereby to enable it to nest in compact relationship.

As shown in Figure 4, a plunger 142 is supported by the member 98 and seats against a

shoulder 144 which is pivotally mounted on the pin 108. The plunger 142 is surrounded by a coil spring 146 and this spring has its opposite end retained in the cup-shaped recess of the cross web 46 as hereinbefore described. The purpose of this spring is such that when the ram piston 86 is projected from the ram cylinder against the roller 110 it will compress the spring 146 against its seat during the load lifting operation. Upon release of the ram piston, as hereinafter described, this spring will force the ram piston back into the cylinder and permit the load carrying member to lower. It is to be noted that this spring is disposed in the longitudinal central axis of the ram piston end of the chassis.

By loosening the four screws 80 (see Figures 1 and 2) the entire unit shown at the lower portion of Figure 2 may be removed from its seats 50 and 52 formed in the hollow inner walls of the chassis. As before noted, this unit comprises the body portion 82 and the connected ram cylinder 84 carrying the ram 86. The plate 75 of the unit forms a shoulder 150 to receive the front end of the upper wall 6 of the chassis. In addition, the body portion 82 is provided with a second shoulder 151 against which a sleeve 152 is clamped. The body portion 82 is provided with an extension 154 having a centralized concentric flange 156 threaded internally as at 158 and concentrically countersunk as at 160 to provide a central well. The ram cylinder 162 is likewise externally threaded on its rear end to engage the threads 158 of the flange 156 so as to screw the ram cylinder in position and maintain it centralized with respect to the center line of the projection 154 on the body portion 82. At its opposite end the ram cylinder sleeve 162 is externally threaded as at 164 to be engaged by the end sleeve 156, see Figure 4. To this end the sleeve 156 is likewise internally threaded as at 166 so that it engages the threads on the outer end of the ram cylinder 162 and this sleeve 156 is likewise provided with a shoulder 168 against which the outer end of the reservoir cylinder 84 is clamped. The outer end of the sleeve 156 is provided with a centralized countersunk portion 170 internally threaded as at 172 to screw threadedly engage a packing ring 174 which maintains the packing 176 in position. By placing the ram cylinder sleeve 152 in position and screwing the ring-like cap 156 in place the concentric sleeves are firmly positioned and held to provide a hollow ram cylinder and a concentrically surrounding reservoir to hold the liquid for the hydraulic system.

Reciprocably mounted within the ram cylinder sleeve 162 is the ram piston 86. This ram piston on its inner end is provided with a threaded centralized stem 178 of relatively small diameter. A ring nut 180 screws upon this stem 178 to confine the usual type of sealing washer 182 and packing 184 between the shoulders formed on the body of the ram cylinder and the collar 180. The opposite end of the ram cylinder 86 is relatively flat to engage the roller 110, as hereinbefore described.

Adjustable means is provided for relieving the pressure in the ram cylinder when the pressure reaches a predetermined maximum. This comprises the passage 186 formed in the body portion 82. The passage 186 communicates with an enlarged bore 188 which extends outwardly to the exterior wall 190 of the boss formed on this head 82. This bore 188 is provided with a

laterally extending, relatively smaller passageway 192 which communicates as at 194 with the reservoir 196. A ball valve 198 is adapted to seat upon a conical seat 200 formed at the junction of the bore 188 and the smaller passageway 186. The cylindrical block 202 bears upon the ball 198. This block has a stud 204 projecting from its opposite end and around which a coil spring 206 is confined, the opposite end of the coil spring bearing against a threaded plug 208 which engages internal threads of the outer end of the bore 188. This threaded plug has a tool-engaging portion 210 for turning. A shank nut 212 closes the terminal portion of this bore. By adjusting the position of the plug 208 the pressure of the spring 206 is accordingly adjusted to determine the pressure which the ball 198 exerts upon the conical seat 200. This in effect determines the pressure by which the ball may be forced outwardly by the liquid pressure in the ram cylinder so that a portion of the liquid may escape via the passage 192 back into the reservoir.

The ram cylinder is provided with a so-called speed pump which is adapted quickly to get the ram up to the load to be lifted, and is likewise provided with a load lifting or pressure pump, which in the present instance is relatively smaller than the speed pump for actually lifting the load once the load is contacted by the ram, and means is provided for cutting out the speed pump so that the pressure pump alone raises the load, and in addition means is provided for operating both of these pumps from a single actuator while permitting one of them to discontinue when the load is reached. In addition, the jack is provided with a pressure release valve for the ram cylinder which lies intermediate the two pumps and is actuated from the same actuator that actuates the pump cylinder. A very compact arrangement of these two spaced apart pumps and the intermediately disposed release valve mechanism, all actuated from a common manual operator, is provided. By reference to Figure 7 it will be noted that the ram cylinder is provided with a relatively large passageway 214 which connects with the well 160 of the ram cylinder. This passageway 214 merges into a bore 216 one end of which is provided with the conical walls 218 to which the bore 214 is centrally connected. At this conical end 218 of the bore 216 there is provided a further, relatively smaller passageway 220 which connects as at 222 with the reservoir 196. At the portion 224 the diameter of the bore 216 is somewhat narrowed and is threaded as at 226. Outwardly of the internally threaded portion 224 of the bore, such bore is provided with a shoulder 228. The bore 224 terminates at the point 230 and the body or body portion 82, which has the side flanges 410 and 418, provides a space therebetween which gives sufficient clearance so that the speed pump cylinder 234 may be inserted in position as shown in Figure 7. This speed pump cylinder comprises the sleeve 234 externally threaded as at 236 at one end and provided at 238, centrally or intermediate its ends, with a polygonal angularly shaped portion, preferably a four or six faced portion, for turning. In addition the outer end of the sleeve is threaded as at 240. The inner end of the sleeve receives a combined valve cage and conical valve. The valve cage comprises a preferably metal block having an annular countersunk shoulder 242 providing an annular wall fitting frictionally tightly within the end of the speed pump sleeve 234. This block

242 provides the ball valve cage. It is formed with a first passage 244 providing a valve seat 246 on which rests the ball valve 248. This valve seat in turn communicates with the piston chamber of cylinder 234. This chamber connects with a second port 250 formed centrally of the ball cage block 242. Passage 242 beyond the ball valve 248 connects with a passage 219 which in turn communicates with the annular enlarged bore portion 216 and this in turn communicates with the passageway 222 leading to the reservoir 196. In addition, the ball valve cage block 242 is provided with a central passage 250 having a conical shaped valve seat controlled by a ball valve 252 which connects with a passage the opposite side of the ball valve cage. In addition there is a third passage 254 in the ball valve cage which passes therethrough from the face that connects with the pump cylinder 234 to a side port 260, hereinafter described. This passage 254 is controlled by a third ball valve 256, spring pressed normally to seat in the direction indicated in Figure 7. As before stated, this passage 254 has a lateral passage 260 which in turn communicates with a transversely extending, relatively larger passage 262 formed in the body 82 and this passage likewise communicates with the enlarged bore 216. The outer face of the ball valve cage 266 is provided with a countersunk portion 264 into which frictionally fits a conical nose 266 having the central passage 268 which communicates with the passage 270 in turn communicating with the ram cylinder well 160. The relatively smaller portion of the conically shaped nose 266 seats upon the centralized aperture in the conical valve seat 218 to close it, except for the passage 268. There is a packing 230 which surrounds the threads 236 of the speed pump sleeve 234 and this packing is held in position by a ring 212. To the threads 240 of the outer end of the speed pump sleeve is threaded a ring 276 provided with a central opening through which the speed pump piston 278 reciprocates. The inner end of this pump piston is provided with the usual type of packing. The outer end of the speed pump piston 278 is provided with a centrally located, threaded bore 280 into which is threaded the shank of a bifurcated head 282 which receives through its bifurcation a cross pin 284 hereinafter referred to, see Figure 5.

Spaced from the bore 224 for the speed pump cylinder formed in the body portion 82 is another bore 286 which is of smaller diameter designed to receive the high pressure pump cylinder. This bore is conically fashioned as at 288 at its inner end and the central portion of this conically fashioned bore communicates as by means of a passage 290 with the well 160 and likewise communicates by means of a passage 292 with the reservoir 196, and this bore 286 likewise communicates by means of the cross passage 262 with the opposite bore 216 which houses the speed pump. An inner portion 294 of this bore 286 is internally threaded and is likewise provided with a countersunk portion 296 which receives a packing 298. This packing is held in position by a collar 300 engaging the external threads 302 of the pressure pump sleeve-like cylinder which is likewise externally threaded as at 304 and 306 and is preferably provided with an unthreaded portion 308 which is multi-sided to enable the sleeve to turn to screw or unscrew it from its threaded bore 294 in the head 32. The outer end of the sleeve 302 receives the packing 310 held in place by the cap 312 engaging the external

threads 306. A high pressure pump piston 314 reciprocates through an opening in the collar 312 in the high pressure pump cylinder 316. The inner end of the high pressure pump cylinder 302 receives a ball valve cage 315 which has a first passageway 318 extending clear through from face to face. This passageway opens onto an enlarged bore terminating in the opposite outer face of the cage 315. This enlarged bore 320 provided a conical seat in which a ball valve 321 rests and seats. In addition the cage 315 is provided with another passageway 324 which provides a conical seat against which the ball 326 seats and this passageway is provided with a lateral portion 328 opening onto the bore 286. The cage is provided with a forward portion of smaller diameter 330 which frictionally seats within an inner wall of the high pressure pump cylinder 302. The outer end of the cage frictionally receives a conically shaped head 332 provided with a central passage 334 and a conical outer nose which seats upon the conical walls 288 hereinbefore mentioned to close the same except for the central passageway 334 which passageway communicates with the passage 298 leading to the ram cylinder well 160, and the passageway 320 communicates by means of the centralized space between the outer end of the cage 315 and the inner face of the nose 332. This space in turn communicates with the passage 334. The outer end of the pressure pump piston 314 is internally threaded to receive the shank 336 of another bifurcated head 338 which head in turn receives the pin 284 in its bifurcations.

Centrally of the two bores 216 and 286, the body portion 82 is provided with a central parallel extending bore 340. The bore 340 is provided with a conical seat in turn provided with a relatively smaller passageway 344 which communicates with a diagonally extending passage 346 which terminates as at 348 in the well 160. A ball valve 350 normally seats upon the conical relief valve seat and the position of this ball valve 350 in turn is controlled by a plunger 352 formed on the end of a release valve stem 354. This stem 354 is threaded as at 356 to engage internal threads 358 on a threaded sleeve-like nut 360 which threads into a boss 362 on the head 82. Packing 364 is held in by the nut 360 and surrounds the shank 354 of the relief valve. The relief valve shank 354 extends outwardly as at 366 and terminates in a head 368 of a universal connection 370 which connects as at 373 with another universal connection 372 in turn connected to a shank 374. This shank is bifurcated as at 376. It will be seen that the two pumps are spaced on each side of the central axis of the ram cylinder and that they lie in a common horizontal plane disposed below the horizontal plane passing through the central longitudinal axis of the ram cylinder. These two pumps are located to the rear of the ram cylinder. The release valve stem 366 is horizontally disposed and its central longitudinal axis lies in the common horizontal plane of the two pumps, substantially midway between the two pumps.

A manual actuator is provided for reciprocating the two pumps in the ram cylinder head 82. To this end a pair of sectors 378 and 380 are provided. Each of these sectors is provided with a pair of notches 382 and 384. In addition they are pinned together as by means of the pin 390. The sectors are provided also with registering apertures 392 and 394. In addition the pin 284 likewise assists in holding the sectors to-

gether. In the registering holes 392 and 394 are located two pivotal pins or shafts 398 and 400 which are in axial registration. The outer ends of each of these pins are threaded to engage in openings 402 and 404 of the bosses 406 and 408 on the plates 410 and 412 of the head 75, see Figures 2 and 8. The pivotal pins 398 and 400 form the main pivot for the furcations 414 and 416 of the handle socket 418. This handle socket is provided with a boss 420 having an aperture 422 to receive a locking shank 424 having a head 426. The boss is likewise provided with an annular countersunk 428 to receive a spring 430 surrounding the shank 424. The lower end of the shank 424 is provided with a locking shoe 432 which engages either of the notches 384 or 382, see Figure 6. By retracting the head 426 the shoe is disengaged from one notch and then by swinging the socket 418 the other notches 20 may be engaged. In this manner the actuator 25 may be used for reciprocating the pistons while either in the vertical position as shown in Figure 5 or while disposed at an angle to the vertical position. It is to be noted that the universal 312 is disposed at the axis of turning 392 of the sectors. The socket 418 receives a sleeve 434. The furcations 376 of the pin 374 engage between a pin 436. This pin is formed on the inner wall of a sleeve 438 having a flange 440 forming an annular keyway 442. This sleeve 438 makes a tight fit with an elongated hollow handle 444 which turnably lies within the socket 418. Means is provided for holding the sleeve 438 and the handle 444 in position within the socket 418. 35 This comprises a pin 446, see Figure 8, having a head 448 and having a spring 450 which normally maintains the head within the socket formed by the shoulder 440 while permitting the sleeve 438 to be turned by turning the handle 434. 40 However, when desired, by pulling outwardly on the head 448 the pin 446 is moved outwardly, whereupon the handle 444 and the tight fitting sleeve 438 may be withdrawn from the handle socket, the pin 439 of the handle 45 freely coming out from position between the furcations 376 of the rod or connector 374. When thus removed, the rod 374 is not accessible for turning. However when the handle and its sleeve with the cross pin 436 engages between the furcations of the rod, then by turning the handle 434 the rod may likewise be turned, which, through the universal connection, turns a valve operating rod 366 to unscrew it from its seat and thereby permit the ball 342 to be moved from its seat by pressure in the ram cylinder. 50 The liquid will then flow from the ram cylinder through the passage 348, the passageway 344, the ball 342, thence through the passage 343 to the reservoir, and the load member will thereupon lower. On the other hand, when the valve rod 352 forces the ball 341 to its seat, and through the oscillation of the handle member and the sectors the high pressure pump piston 366 is operated, liquid will be drawn from the reservoir through the passage 292, thence into bore 286, thence through passageway 328, past the ball 326 into the high pressure pump. Upon movement of the pump piston downwardly this liquid will then be forced through the passage 318, the ball 322, thence into passage 334, passage 290, into the ram cylinder, to move the ram outwardly of the ram cylinder. 60 65 70

In the operation of the complete device, starting with the jack in position under the load and 75 with the load lever 88 in lowered position and

not contacting the load, oscillation of the handle 434 will, through the connections 282 and 284 and the piston 278, reciprocate the speed pump and the high pressure pump simultaneously. Both pumps will create pressure. Their combined efforts, mainly due to the larger capacity of the speed pump, will cause the load member 88 quickly to ascend or rise to contact with the load. During the reciprocation of the speed pump 278 liquid will be drawn by the piston as it moves toward the right, see Figure 7, from the reservoir through the port 220 to the space 218, thence through the lateral port 219, past the ball valve 248 into the speed pump cylinder chamber. Upon compression of this same piston 278 this liquid will flow through the port 250, past the ball valve 252, through the port 268 and port 214 into the ram cylinder chamber. When the ram has contacted the load and a predetermined pressure is created, the piston will then continue to operate, but due to the back pressure thus created in the ram cylinder being higher than the setting of the spring 260, any liquid compressed in the speed pump chamber will be forced through the port 253, past the ball valve 255, out through lateral chamber 260, thence into the space 261, thence back through port 220 to the reservoir, and thus at this pressure the speed pump is thrown out of effective operation, and from then on the pressure pump 314 operates alone to raise the load in the manner hereinbefore described. In any event, the spring 206 of the pressure relief valve 198 can be set so that if the pressure created by the pressure pump in the well 160 becomes too great the pressure of the liquid will force the spring 206 backward to permit the liquid to pass through the port 192 back into the reservoir.

Obviously the invention is not limited to the specific details of construction disclosed herein but is capable of other modifications and changes without departing from the spirit and scope of the appended claims.

Having thus described the invention, what is claimed as new and desired to be secured by Letters Patent is:

1. A hydraulic jack comprising a body having means providing a ram cylinder and a reservoir, said body providing a ram cylinder chamber in association with said ram cylinder, a ram reciprocable in said ram cylinder, pumping means for drawing liquid from said reservoir and forcing it into said ram cylinder to cause said ram to raise a portion of the jack to engage the load, said pumping means including a pump cylinder and a piston reciprocable therein, said pump cylinder carrying a valve cage provided with a ported nozzle, means forming a passage interconnecting the port in said nozzle with said ram cylinder, means providing an annular chamber around said nozzle, means connecting said annular chamber with the reservoir, means providing a pair of additional liquid conducting passages in said valve cage, each of said passages interconnecting the pump cylinder chamber with said annular chamber, one of said passages being governed by a spring actuated relief valve adapted to be forced from its seat by the creation of a predetermined pressure in said pump chamber to pass liquid from said chamber back to the reservoir, and the other of said valves being adapted to be relieved from its seat to permit liquid to flow from said reservoir into said pump chamber, and a third valve controlling the passage interconnecting said pump chamber and the passage in said nozzle.

said third valve closing said passage upon the creation of a predetermined pressure in said ram cylinder that is greater than in said pump chamber, a second pumping means comprising a relatively smaller diameter pumping cylinder, a relatively smaller piston reciprocable in said smaller diameter pumping cylinder, a second valve cage carried by said second mentioned cylinder, a conical nozzle carried by said second cage, said nozzle having a valved passage connecting said pump chamber with said ram cylinder, means providing an annular passage surrounding said second conical nozzle, said second annular passage about said second nozzle connecting with the reservoir, and an additional passage formed in said second valve cage connecting said pump cylinder with said second annular passage, a valve controlling said last mentioned passage, said valve being drawn from its seat upon the creation of a suction in the pump chamber, and a release valve disposed between said pump cylinders, said release valve comprising a bore in said base, a common passage connected to said release valve bore and to the annular passages surrounding the conical nozzles of the two pumps, said release valve bore communicating with the ram cylinder, a valve controlling said communication, and a manually actuatable operating means to control said valve.

2. An hydraulic jack comprising a base or chassis, forward and rearward pairs of wheels mounted on said chassis, a lifting lever pivotally mounted on said chassis and carrying a load support, said lifting lever having a power arm depending within said chassis, the rear end of said chassis having an end opening provided with fastening means apertures adjacently disposed in spaced relation around said opening and a power unit comprising a substantially vertical plate having normally projecting from the face thereof an outwardly projecting ram cylinder and surrounding reservoir, there being a piston longitudinally slidable in said ram cylinder, said plate having extending in the opposite directions at right angles thereto and in spaced relation on opposite sides of the ram cylinder, parallel vertical plates disposed in spaced relation whereby when said first mentioned vertical plate is bolted to the rear end of said chassis by means of fastening members passing through the spaced openings surrounding said main opening of the chassis the power unit is bolted in position with the end of the ram of the power unit confronting the depending end of the load lifting lever, said power unit including a pair of spaced pump cylinders formed in spaced bores in that end of the power unit that lies between the parallel spaced vertical plates and said vertical end plate, and a handle member having a yoked bottom portion pivotally mounted in the opposed vertical plates of said power unit, said handle including depending arm portions having pivotal connections with the outer ends of each of the pistons reciprocable in said pump cylinders, the body of the power unit between said pump cylinders being formed with a pressure relief valve bore communicating with the ram cylinder and a turnable pressure relief valve mounted in said pressure relief valve bore, and said bore and two pump cylinders being disposed in a common horizontal plane between said spaced parallel vertical plates, and universal connections between said turnable pressure release valve and said handle, one of said universal connections lying

in the pivotal axis of said handle, and turnable actuating connections carried by said handle for turning said pressure relief valve.

3. An hydraulic jack comprising a base or chassis, forward and rearward pairs of wheels mounted on said chassis, a lifting lever pivotally mounted on said chassis and carrying a load support, said lifting lever having a power arm depending within said chassis, the rear end of said chassis having an end opening provided with fastening means apertures adjacently disposed in spaced relation around said opening and a power unit comprising a substantially vertical plate having normally projecting from the face thereof an outwardly projecting ram cylinder and surrounding reservoir, there being a piston longitudinally slidable in said ram cylinder, said plate having extending in the opposite directions at right angles thereto and in spaced relation on opposite sides of the ram cylinder, parallel vertical plates, said plates having registering bosses therein, a pair of stationary shafts supported in said bosses with the inner ends of said shafts disposed in spaced apart relation, a handle pivotally mounted on said shafts and a pair of interconnected sector arms likewise pivotally mounted on the inner end of said shafts, the adjacent end of the body of the power unit between said plates being formed with a pair of parallel bores disposed on opposite sides of the ram cylinder and slightly below the central longitudinal axis of the ram cylinder, said bores being located in a common horizontal plane, pump cylinders in said bores, one of said pump cylinders being larger than the other, pistons reciprocable in said pump cylinder and extending outwardly between said plates, said spaced sectors having connections therefrom to the pistons in said pump cylinders for actuating the latter on pivotal movement of said handle, the body of said power unit between the bores forming said pump cylinders being provided with an additional bore communicating with said ram cylinder, said bore lying in the same common plane with the bores of said pump cylinder, and a pressure relief valve turnably mounted in said bore, a turnable shaft mounted in said handle, and universal connections between said turnable shaft and the outer end of said release valve, one of said universals being disposed directly at the central axis of said pair of inwardly extending spaced apart shafts on which the handle is pivotally mounted.

4. An hydraulic jack comprising a body having means providing a ram cylinder and a reservoir, said body providing a ram cylinder chamber in association with said ram cylinder, a ram reciprocable in said ram cylinder, pumping means for drawing liquid from said reservoir and forcing it into said ram cylinder to cause said ram to raise a portion of the jack to engage the load, said pumping means including a pump cylinder and a piston reciprocable therein, said pump cylinder carrying a valve cage provided with a ported nozzle, means forming a passage interconnecting the port in said nozzle with said ram cylinder, means providing an annular chamber around said nozzle, means connecting said annular chamber with the reservoir, means providing a pair of additional liquid conducting passages in said valve cage, each of said passages interconnecting the pump cylinder chamber with said annular chamber, one of said passages being governed by a spring actuated relief valve adapted to be forced from its seat by the creation of a predetermined pressure in said pump chamber

to pass liquid from said chamber back to the reservoir, and the other of said valves being adapted to be relieved from its seat to permit liquid to flow from said reservoir into said pump chamber, and a third valve controlling the passage interconnecting said pump chamber and the passage in said nozzle, said third valve closing said passage upon the creation of a predetermined pressure in said ram cylinder that is greater than in said pump chamber, a second pumping means comprising a relatively smaller diameter pumping cylinder, a relatively smaller piston reciprocable in said smaller diameter pumping cylinder, a second valve cage carried by said second mentioned cylinder, a conical nozzle carried by said second cage, said nozzle having a valved passage connecting said pump chamber with said ram cylinder, means providing an annular passage surrounding said second conical nozzle, said second annular passage about said second nozzle connecting with the reservoir, and an additional passage formed in said second valve cage connecting said pump cylinder with said second annular passage, a valve controlling said last mentioned passage, said valve being drawn from its seat upon the creation of a suction in the pump chamber, a valve bore interconnecting said ram cylinder and the annular passages surrounding the conical nozzles of the two pumps, a release valve in said valve bore between said pump cylinders for selectively opening and closing said valve bore, and manual operating means to control said release valve.

5. An hydraulic jack comprising a base or chassis, forward and rearward pairs of wheels mounted on said chassis, a lifting lever pivotally mounted on said chassis and carrying a load support, said lifting lever having a power arm depending within said chassis, the rear end of said chassis having an end opening provided with fastening means apertures adjacently disposed in spaced relation around said opening and a power unit comprising a substantially vertical plate having normally projecting from the face thereof an outwardly projecting ram cylinder and surrounding reservoir, there being a piston longitudinally slidable in said ram cylinder, said plate having extending in the opposite directions at right angles thereto and in spaced relation on opposite sides of the ram cylinder, parallel vertical plates disposed in spaced relation whereby when said first mentioned vertical plate is bolted to the rear end of said chassis by means of fastening members passing through the spaced openings surrounding said main opening of the chassis the power unit is bolted in position with the end of the ram of the power unit confronting the depending end of the load lifting lever, said power unit including a pump cylinder formed in a bore in that end of the power unit that lies between the parallel spaced vertical plates and said vertical end plate, and a handle member having a yoked bottom portion pivotally mounted in the opposed vertical plates of said power unit, said handle including a depending arm portion having pivotal connections with the outer end of the piston reciprocable in said pump cylinder, the body of the power unit adjacent said pump cylinder being formed with a pressure release valve bore communicating with the ram cylinder and a turnable pressure release valve mounted in said pressure release valve bore, and said bore and pump cylinder being disposed in a common horizontal plane between said spaced parallel vertical plates, and universal connections between

said turnable pressure release valve and said handle, one of said universal connections lying in the pivotal axis of said handle, and turnable actuating connections carried by said handle for turning said pressure release valve.

6. An hydraulic jack comprising a base or chassis, forward and rearward pairs of wheels mounted on said chassis, a lifting lever pivotally mounted on said chassis and carrying a load support, said lifting lever having a power arm depending within said chassis, the rear end of said chassis having an end opening provided with fastening means apertures adjacently disposed in spaced relation around said opening and a power unit comprising a substantially vertical plate having normally projecting from the face thereof an outwardly projecting ram cylinder and surrounding reservoir, there being a piston longitudinally slidable in said ram cylinder, said plate having extending in the opposite directions at right angles thereto and in spaced relation on opposite sides of the ram cylinder, parallel vertical plates, said plates having registering bosses therein, a pair of stationary shafts supported in said bosses with the inner ends of said shafts disposed in spaced apart relation, a handle pivotally mounted on said shafts and a pair of interconnected sector arms likewise pivotally mounted on the inner end of said shafts, the adjacent end of the body of the power unit between said plates being formed with a bore disposed adjacent the ram cylinder and slightly below the central longitudinal axis of the ram cylinder, a pump cylinder
